UNITED STATES PATENT OFFICE.

EUGÈNE NICOLINI, OF PARIS, FRANCE, ASSIGNOR TO SOCIÉTÉ D'ELECTRICITÉ DE PARIS, OF PARIS, FRANCE, A FRENCH JOINT-STOCK COMPANY.

TRAVELING CHAIN GRATE.

Application filed January 2, 1926, Serial No. 78,770, and in France April 16, 1925.

- This invention relates to traveling chain grates for mechanical stoking. These mechanical chain grates, when provided with air-draft casings, present the inconvenience that the endless chains are affected by the combustion of coal dust which accumulates in these casings or air compartments, if for any reason they are not cleaned or emptied regularly.
- 10 The invention has for its object to provide a mechanical chain grate partitioned off into separate air compartments with a view to suppressing the accumulation of coal dust in the compartments so formed, while however keeping the compartments practically air-tight as is necessary for the satisfactory operation of the draft.

Upon the annexed drawing to which reference is made in the following description and upon which the same letters and characters designate the same elements or parts,

20 Figure 1 is a partial longitudinal section of a chain grate arranged in conformity with the invention;

Figures 2 and 3 respectively are sections along the lines 2—2 and 3—3 of Figure 1;

Figure 4 is a diagram of the complete chain grate.

30 The traveling grate is formed, as usual, by an endless chain A, of which the links constitute the bars of the grate; this chain A travels between two side frames f and is driven by any suitable means, not shown in the drawing.

The main feature of the improved chain grate is that the baffles C¹ C² C³ arranged between the upper run a¹ and the lower run a of the chain, so as to form separate air compartments, are themselves partitioned off into chambers each enclosing packing means as hereinafter described.

40 The lower or return run a of the chain slides over a metal plate b secured to the side frames f by any convenient means. This plate rests upon cross members t, to which it is attached by clips t⁰, the cross members t being fastened to the side frames f and arranged preferably in the same vertical planes as the transverse baffles C¹ C² C³, which are spaced at suitable intervals apart.

50 The baffles, which divide the space between the said runs a, a¹ of the chain into a certain number of air-draft compartments O¹, O², O³ . . . each comprise transverse

channel beams c¹ suitably secured to the side frames f, a plurality of parallel angle-irons c² secured beneath the channel beams and a plurality of partitions c, of general vertical direction, forming parallel spaces closed at their top ends, these partitions being secured to the respective angle-irons c² and supported by the channel beams c¹. The baffles C¹, C², C³ . . . are arranged immediately beneath and against the upper run a¹ of the chain A and their partitions c extend down towards the lower run a stopping short at a height such that in case of breakage of one of the links of the grate-forming chain A, the broken parts still adhering to their pivot pins in the path of the said run a can pass under the partitions c without catching or hooking on to them.

55 Each of the parallel spaces or chambers formed between consecutive partitions c in the baffles encloses a freely rotatable tube T which rests across the lower run a of the chain A.

60 The air-draft for combustion enters the compartments O¹, O², O³ . . . by lateral openings d formed in the side frames f.

65 The several compartments are separated from one another by the baffles which form practically air-tight divisions. Leakages of air from any compartment to the adjacent ones can only be very small and is in practice negligible, for any air tending to escape from one compartment to another through the restricted and labyrinthine passages afforded by the tubes T, the partitions c, the transverse ribs n and the bosses g with which the links or bars of the chain grate are provided, will generate eddies opposing the passage of the air. In practice the obturating function of these eddies is 70 completely effective.

75 It has already been stated that the partitions c are of such dimensions as to prevent broken links of the chain A from hooking on to them; the broken parts of such links still fast to the run a of the said chain pass by the tubes T, merely lifting the latter, which then automatically resume their working position by reason of their weight. This result can be obtained still more effectually 80 by subdividing each tube T into a suitable number of elements or rollers t¹, t², t³ . . . see Figure 2. A spacer bar e fixed at its ends upon the side frames f passes 85 through the interior of each tube T, the lat-

ter being either in one piece or in several elements, the position of this spacer bar being selected so as to allow in all cases the rotation of the said tube when a broken link of the chain A comes into contact with it.

Particles of coal passing between the bars of the upper run a^1 of the grate on which the combustion takes place, fall upon the 10 lower run a which carries them continually to the front of the grate where they are discharged automatically in any convenient manner.

A certain amount of clearance necessarily 15 exists between the side plates f and the lateral edges of the lower or return run a of the chain A, for the purpose of allowing the passage of the ends of the connecting pins in each link of the chain. Air under 20 pressure in the compartments might therefore escape through the interstices so presented. In order to prevent such leakage and obtain substantially air tight seals between the lateral portions of the lower run 25 a of the chain A and the side frames f there is preferably adopted the following device which obviates any damage in case of accidental breakage of the bars.

In each air-draft compartment O^1 , O^2 , O^3 30 . . . and along each of the lateral edges of the lower run a , there is arranged a sheet metal flap of suitable width, made in two sections g , g^1 respectively fixed upon bars h , h^1 pivoted together upon a pin i . This 35 flap g , g^1 has its opposite extremities curved upwards, see Figure 1, and rests normally by its own weight upon the bars or links of the lower run a of the chain.

The bar h^1 has a cranked extension h^2 , 40 itself pivoted upon a fixed pin l , each of the bars h^1 with its extension h^2 forming a bent lever pivoted at one end at l and secured at its other end to the bar h which is pivotally connected to it by the pin i .

45 This cover device prevents leakage downwards along the sides of the draft compartments O^1 , O^2 , O^3 along the lateral edges of the chain grate A, and in case of breakage of the components of the grate, if the pieces 50 still fast to the pivot pins of the links come to abut upon the part g of the flap as at m , Figure 1, they cause the bent lever h^1 , h^2 with which the part g^1 is fast, to turn about its pivot l , thereby lifting the connected end 55 of the other bar h ; in these conditions, all the movable parts of the device are brought into the position indicated in dotted lines in figure 1 of the drawing.

After the passage of the damaged bars, 60 these movable parts resume their normal position (shown in full lines) by their own weight.

Satisfactory working of the grate is thus assured without any disadvantages.

65 The improved chain grate may also be

provided in the guide plate b over which the lower run a of the grate A slides, with a number of openings p adapted to be closed at will by hinged shutters. By this arrangement, it becomes possible to utilize the grate 70 with forced draft, with the openings p closed, or else to utilize it with natural draft with these openings p uncovered.

What I claim is:—

1. A chain grate, comprising an endless 75 traveling chain including fire-bar elements, baffles dividing the space between the upper and lower runs of said chain into a plurality of draft compartments, said compartments being adapted to receive separate supplies 80 of air, each of said baffles including a plurality of vertical walls delimiting parallel chambers, and rotatable members enclosed in the lower parts of said chambers, said rotatable members resting upon the inner face 85 of the lower run of said chain and sealing said draft compartments along the lower edges of said baffles.

2. A chain grate, comprising an endless 90 traveling chain including fire-bar elements, baffles dividing the space between the upper and lower runs of said chain into a plurality of draft compartments, the upper run of said chain traveling over the top ends of said baffles, the lower ends of each of said baffles including at least three substantially vertical partitions delimiting parallel chambers, tubular members enclosed in the lower parts of said chambers, said tubular members resting upon the lower run of said chain 100 to form an air seal but being adapted to yield by rising in their respective chambers to permit passage of an obstruction, and means for positioning said tubular members in said chambers while allowing them to 105 yield by rising therein.

3. A chain grate, comprising an endless 110 traveling chain including fire-bar elements formed by links of said chain, baffles dividing the space between the upper and lower runs of said chain into a plurality of air compartments, the upper run of said chain traveling over and in contact with said baffles, each of said baffles including a plurality 115 of partitions forming chambers, and tubular rolling elements enclosed in the chambers afforded between said partitions, said rolling elements resting freely upon the lower run of said chain and being adapted to yield individually for the passage of an obstruction upon the lower run of said chain.

4. A chain grate comprising an endless 125 traveling chain including fire-bar elements formed by links of said chain, baffles dividing the space between the upper and lower runs of said chain into a plurality of draft compartments, the upper run of said chain traveling over and in contact with said baffles, each of said baffles including at least 130 three partitions extending down towards the

lower run of said chain but stopping short thereof at a height sufficient to allow passage of broken parts of said chain, said partitions forming chambers between them, and 5 tubular rollers positioned in the lower parts of said chambers, each of said rollers resting freely upon the lower run of said chain to form an air seal and being displaceable independently of the adjacent rollers.

10 5. A chain grate comprising an endless traveling chain including fire-bar elements, side frames along the lateral edges of said chain, baffles dividing the space between the upper and lower runs of said chain into a 15 plurality of draft compartments adapted to receive individual supplies of air, said baffles including means extending lengthwise of said baffles for minimizing leakage of air over the lower run of said chain from one 20 to another of said compartments, and other means extending longitudinally of said chain for minimizing leakages of air between said side frames and the lateral edges of the lower run of said chain, said last mentioned means 25 consisting of hinged flap sections arranged at each side of each of said compartments and pivotally attached to one of said baffles, said flaps extending along the lateral edge of the lower run of said chain 30 for the entire length of the respective compartment and covering the longitudinal joint

between said edge and the adjacent part of said side frame.

6. A chain grate comprising an endless traveling chain including fire-bar elements, 35 side frames along the lateral edges of said chain, baffles dividing the space between the upper and lower runs of said chain into a plurality of draft compartments adapted to receive individual supplies of air, said baffles 40 including means extending along said baffles for minimizing leakages of air from one to another of said compartments, and other means extending longitudinally of said chain at the sides of each compartment for minimizing leakages of air between said side frames and the lateral edges of the lower run of said chain, said last mentioned means 45 consisting of pairs of hinged flap sections and bars fixed to the sections of each pair, 50 said bars being pivotally connected together, one of said bars being pivotally attached to one of said baffles and said flap-sections resting freely by their own weight upon the lower run of said chain but being adapted 55 to yield by upward pivotal movement to allow passage of obstructions on the chain, said flap-sections thereafter returning to their normal position.

In witness whereof I affix my signature.

EUGÈNE NICOLINI.
